(57) **CLAIM**

(21) Appl. No.: **29/130,998**

The ornamental design for a graspable portion of window hold open mechanism, as shown and described.

(22) Filed: **Oct. 12, 2000**

DESCRIPTION

(51) LOC (7) Cl. **08-06**

FIG. 1 is a rear, side and top perspective view of my design for a graspable portion of window hold open mechanism;

(52) U.S. Cl. **D8/321**; D8/306; D8/307

FIG. 2 is a bottom view thereof;

(58) Field of Search D8/300, 306, 307, D8/321; D12/183; 49/324, 350, 460, 397, 357; 292/218; 296/146.16; 74/501.6

FIG. 3 is a plan view thereof;

FIG. 4 is an elevation view thereof from the same side as in FIG. 1;

(56) **References Cited**

FIG. 5 is an elevation view thereof from the side opposite that in FIG. 4;

U.S. PATENT DOCUMENTS

FIG. 6 is a front elevation view thereof; and,

- D. 197,733 * 3/1964 Orenstein .
D. 254,772 * 4/1980 Buck, Jr. D8/306
D. 371,290 * 7/1996 Ozark D8/307
2,745,692 * 5/1956 Persson .
3,974,753 * 8/1976 Blomgren et al. .

FIG. 7 is a rear elevation view thereof.

The portion of the graspable portion of window hold open mechanism shown in dotted lines for illustrative purposes only in FIGS. 1-7 does not constitute a part of the claimed design.
